PLIER TYPE WRENCH

Joel Hahn, Beatrice, Nebr.

Application October 1, 1942, Serial No. 460,435

2 Claims.

(Cl. 81—87)

This invention relates to quick acting plier type wrenches, and aims to provide a wrench wherein the movable jaw thereof may be readily and easily moved into gripping relation with respect to the stationary jaw, novel means being provided for securing the movable jaw to its positions of adjustment, insuring against the wrench slipping or losing its grip on the article with which it is used, when pressure is directed to the wrench.

An important object of the invention is to provide a wrench of this type having means whereby the pivot point of the movable jaw may be adjusted, after the movable jaw has been slid into operative gripping relation with the stationary jaw, thereby adapting the wrench for use in connection with articles of various sizes.

A still further object of the invention is to provide means for making a final adjustment of the movable jaw with respect to the stationary jaw, to the end that an exceptionally fine adjustment of the movable jaw will be assured.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 is an elevational view of a plier type wrench, constructed in accordance with the invention.

Figure 2 is a plan view thereof.

Figure 3 is a fragmental sectional view through the movable jaw and its operating lever.

Figure 4 is a sectional view taken on line 4—4 of Fig. 1.

Figure 5 is a sectional view taken on line 5—5 of Fig. 1.

Figure 6 is an elevational view of a modified form of plier type wrench.

Figure 7 is a sectional view taken on line 7—7 of Fig. 6.

Figure 8 is a sectional view taken on line 8—8 of Fig. 6.

Referring to the drawings in detail, the reference character 5 designates the shank of the stationary jaw, which has one end thereof formed into a handle 6, the opposite end being formed into a jaw portion 7 which is extended at an oblique angle with respect to the shank 5,

as clearly shown by Figure 3 of the drawings.

The shank 5 is substantially wide, and is provided with pivot openings 8 adapted to align with the openings 9 formed in the inner end of the lever 10. The lever 10 is constructed of a length of heavy sheet metal material bent longitudinally upon itself, providing spaced flanges 11, adapted to straddle the shank 5 of the stationary jaw. The inner end of the lever 10 extends beyond the inner edge of the shank 5, where it is provided with an opening, in which the pivot pin 12 is held. The pivot pin 12 also passes through an elongated opening 13 formed on the inner end of the movable jaw 14 of the wrench. This movable jaw 14 is provided with a yoke 15 which is fitted over the shank 5 of the stationary jaw, and is constructed to slide longitudinally thereof. The movable jaw indicated at 16, is also disposed at an oblique angle with respect to the shank 5 so that it will lie in parallel relation with the stationary jaw 7.

The free end of the lever 10 is formed with a threaded opening in which the threaded end of the securing rod 17 moves, the forward end of the securing rod engaging the shoulder 18 of the yoke 15, to the end that by rotating the securing rod in one direction, the movable jaw may be moved into close engagement with the object over which the jaws have been positioned, thereby insuring against the wrench slipping, when excessive strain is brought to bear thereon in moving the object.

The reference character 19 designates the pivot pin of the wrench that connects the lever 10 with the shank 5. The pivot pin is formed with an annular groove at one end thereof, which groove is adapted to be engaged by the spring fingers 20, which snap into place within the groove, securing the pivot pin 19 against movement after it has been positioned in alining openings of the flanges of the lever 10 and shank 5. Due to this construction of the pivot pin, it will be obvious that by removing the pin and placing it in other alining openings, the initial movement of the movable jaw with respect to the stationary jaw may be adjusted quickly and accurately. It should be obvious that after the adjustment has been made in this way, the operation of the rod 17 will act to move the movable jaw into close engagement with the object, making the final adjustment so that the jaws of the wrench will securely grip the object.

The chain indicated at 21 is provided for securing the pin 19 to the wrench to insure against loss of the pin.

From the foregoing detailed disclosure, it is believed that the operation of the plier type wrench will be obvious, and that further description as to the operation of the wrench is unnecessary.

In the form of the invention as shown by Figure 6 of the drawings, the shank of the wrench, which is indicated by the reference character 22, is formed with an elongated opening in which the block 23 operates. The block 23 is formed with laterally extended trunions 24 that move in openings formed in the flanges 25 of the lever 26. The movable jaw in this form of the invention is indicated by the reference character 27 and is provided with an elongated opening in which the pin operates, the pin 28 being carried by the lever 26.

An adjusting screw 29 is provided, which screw operates on the threaded portion of the rod 30, that is swiveled to the block 23, to the end that by rotating the adjusting screw 29 the pivot point between the lever 26 and movable jaw may be varied, to adjust the movable jaw with respect to the stationary jaw 29 and adapt the wrench for positioning on varied sized articles. In this form of the invention, the securing rod 31 is provided for engaging the shoulder 32 of the movable jaw, to secure the movable jaw against movement, after it has been adjusted.

Having thus described the invention, what is claimed is:

1. In a quick acting wrench, a stationary jaw comprising a shank and a handle, a movable jaw including a yoke, slidable over the shank of the stationary jaw, a lever pivotally and slidably connected with the yoke of the movable jaw and being pivotally connected with the handle of the stationary jaw, said lever adapted to be gripped with the handle of the stationary jaw in operating the movable jaw, a shoulder extending rearwardly from the yoke adjacent to the rear edge thereof, and an adjustable threaded rod extending through the lever and adapted to engage said shoulder restricting movement of said movable jaw in one direction.

2. In a quick acting wrench, a stationary jaw comprising a shank and a handle, a movable jaw including a yoke, slidable over the shank of the stationary jaw, a shoulder extending rearwardly from the yoke, a lever pivotally and slidably connected with said yoke, said lever being pivotally connected with the shank of the stationary jaw, said lever embodying a length of metal bent longitudinally upon itself, providing spaced longitudinal flanges adapted to straddle the shank of the stationary jaw, a securing rod disposed between the flanges of the lever and having threaded connection with the lever, and said rod adapted to engage the shoulder, restricting movement of the movable jaw in one direction.

JOEL HAHN.
